PNEUMATIC PEENING AND MARKING TOOL

Milo W. Kibbe, Jr., New Haven, Conn., assignor to Plane Parts, Inc., New Haven, Conn., a corporation of Connecticut

Filed Nov. 28, 1958, Ser. No. 777,053

2 Claims. (Cl. 121—17)

This invention relates to a pneumatic peening and marking tool, and more particularly to a pneumatic peening and marking tool in which there is provided a self-oscillating piston which acts as the vibrating element.

This application is a continuation-in-part of my application Serial No. 648,663, filed March 26, 1957, now abandoned.

Self-oscillating pistons are not in themselves new. However, heretofore they have principally been used in hammer type devices in which the force generated by each stroke is the important thing, and the speed with which the strokes are delivered is secondary.

On the other hand, in pneumatic peening and marking tools heretofore available, in which the vibrating element must be rapidly oscillated to produce a reasonably continuous marking, the vibrating element is generally oscillated by means of complicated valve arrangements or special air supply arrangements which not only are expensive to own but are not easily adjusted and kept adjusted. In the case of those tools which require a special air supply, the cost of providing this supply adds greatly to the cost of owning and operating the tool.

It is an object of this invention to provide a peening and marking tool which is pneumatically driven from a conventional source of air pressure available in most manufacturing plants.

It is a further object of the present invention to provide a pneumatic peening and marking tool in which no special valve arrangement is necessary to drive the vibrating element.

It is a still further object of the present invention to provide a pneumatic peening and marking tool in which the vibrating element is automatically and rapidly reversed by the construction of the vibrating element and the tool itself, the parts of the tool being simple to make and assemble and the tool itself being easy to maintain.

Other and further objects of the present invention will be apparent from the following description and the appended claims taken together with the accompanying drawing, in which:

Fig. 1 is a sectional elevation of the tool according to the invention; and

Fig. 2 is a cross sectional elevation view taken along line 2—2 of Fig. 1.

As seen in Fig. 1, the pneumatic peening and marking tool according to the invention consists of a body 10 with an enlarged handle portion 11 on one end thereof. Extending into the body 10 from one end thereof is a bore 12 which has an enlarged outer end 12a. The outer portion of the enlarged outer end is internally threaded. A driver bushing cap 13 is threaded into the threaded portion of the enlarged outer end 12a of the bore 12. The driver bushing cap 13 also has a bore therethrough. A nylon driver bushing 14 is inserted into the end of the driver bushing cap and surrounds the bore in the driver bushing cap. A driver 15 is slidably positioned in the bore 12 and extends through the bore

2

in the driver bushing cap 13 and through the nylon driver bushing 14. The driver 15 has a recess 16 in the end thereof which projects from the driver bushing cap, and fitted into the recess is an exchangeable peening or marking tool 17.

The collar 19 is mounted on the driver 15 within the unthreaded part of the enlarged end 12a of the bore 12. A return spring 20 is positioned between the collar 19 and the inner end of the driver bushing cap 13, which spring tends to urge the collar 19 away from the driver bushing cap.

The enlarged handle portion 11 of the body 10 has a cylinder bore 21 therein, which cylinder bore joins the bore 12. The cylinder bore 21 has an enlarged outer end 21a. The wall of the enlarged handle portion 11 has a threaded air inlet 22 therein which opens into the enlarged outer end 21a. The wall of the enlarged handle portion 11 also has two diametrically opposed air outlets 23 therein which open out of the cylinder bore 21 adjacent said air inlet 22. The wall of the body 10 also has a further air outlet 18 therein, which outlet opens out of the end of the cylinder bore 21 away from the air inlet 22. This air outlet is always at least partially open. The length of the driver from the collar 19 to the inner end thereof plus the thickness of the collar and the spring 20 when it is compressed being greater than the distance from the inner end of the driver bushing cap 13 to the edge of the air outlet 18 closest thereto.

A differential piston 24 is slidably positioned in the cylinder bore 21. It has a larger diameter part 25 in the enlarged outer end 21a of the cylinder bore and a smaller diameter part 26 in the cylinder bore 21. The end of the smaller diameter part 26 bears against the end of the driver 15 which projects into the cylinder bore 21. The differential piston 24 has a larger end area 27 on the end of the larger diameter part 25 and a smaller area 28 between the larger diameter part 25 and the smaller diameter part 26, which area is the difference between the cross sectional area of the larger diameter part 25 and the cross sectional area of the smaller diameter part 26.

The differential piston 24 has an axial bore 29 therein which opens out of the piston at the larger end area 27. The piston also has four piston bore outlets 30, extending at right angles to each other, which open out of the axial bore 29 of the piston into a circumferential groove 30a in the smaller diameter part 26.

An end cap 32 is threaded into the threaded end 31 of the enlarged outer end 21a of the cylinder bore 21.

In the position of the tool shown in Fig. 1, it is ready to start a cycle. The piston bore outlets 30 open out of the smaller diameter part 26 into the groove 30a in the piston and through air outlets 23. The length of the differential piston 24 is such that the larger diameter part 25 is positioned in relation to the air inlet 22 such that air admitted through air inlet 22 will apply air pressure against the smaller area 28. The end of the smaller diameter part 26 is against the end of the sliding rod 15.

When the air under pressure from a conventional source of steady air pressure is admitted through inlet 22, it applies pressure to the smaller area 28. Since the space within the enlarged outer end 21a of the cylinder bore 21 is open to the atmosphere through the axial bore 29 and the outlet 23, the pressure on the smaller area 28 will be larger than the pressure on the larger end area 27, and the piston 24 will be urged toward the end cap 32. When the piston 24 has moved far enough so that the piston bore outlets 30 are open to the air inlet 22, however, the space within the enlarged outer end 21a of the cylinder bore 21 will be open to the

air pressure through the axial piston bore 29. The air pressure will then be applied to both the larger end area 27 and the smaller area 28, and the difference in total pressure will drive the piston 24 toward the driver 15. The momentum built up during the movement under the effect of the differential air pressure will cause the piston 24 to strike the sliding rod 15, which in turn will transmit the impact to the exchangeable tool 17. At this point the piston bore outlets 30 and the groove 30a will be opposite the air outlets 23 and the space within the enlarged outer end 21a will be vented to the atmosphere. The piston will then be ready to repeat the cycle.

Air pressure through air inlet 22 has been steady throughout the cycle, no valve arrangement being necessary to shut it off or to direct it against the smaller end of the piston 24. Thus a conventional supply of air under pressure can be used to oscillate the piston 24.

By reason of the provision of the groove 30a in the piston, and the four radially directed outlets from the piston bore which open into the groove, the air is quickly and easily released from behind the larger end area of the piston. Moreover, since there are four outlets 30, and there are two diametrically opposed outlets 23 in the body 10, if any one of the outlets 30 is aligned with either of the outlets 23, one of the other outlets 30 will be aligned with the other outlet 23, thus further facilitating the quick release of the air driving the piston on its driving stroke.

In addition to the structure which provides for a quick release of the air behind the piston, there is provided the air outlet 18 which always vents the space at the inner end of the cylinder bore 21. There can thus never be an air cushion to slow down the stroke of the piston. The only reversing force is the return spring 20, which will act much more quickly than an air cushion and spring combined.

This structure thus provides for quick release of the air pressure driving the piston on its driving stroke and for quick reversal of the piston. This promotes rapid operation of the device which results in the production of a substantially continuous line by the tool 17.

It is thought that the invention and its advantages will be understood from the foregoing description and it is apparent that various changes may be made in the form, construction and arrangement of the parts without departing from the spirit and scope of the invention or sacrificing its material advantages, the form hereinbefore described and illustrated in the drawings being merely a preferred embodiment thereof.

I claim:

1. In a pneumatic peening and marking tool, the combination of a tool body having an enlarged handle portion on one end thereof, said body having a bore in the other end thereof with an enlarged outer end, a driver bushing cap in the outer portion of said enlarged outer end, a driver having a collar thereon in said bore with said collar in said enlargement, said driver having a tool holding recess in the end thereof projecting from the body, a spring in said enlargement between said driver bushing cap and said collar, said spring urging said driver away from the end of said body from which said

driver projects, the enlarged handle portion of said body having a cylinder bore therein joining the bore in said body, said handle portion having therein at least one threaded air inlet to said cylinder bore and two diametrically opposed air outlets from the portion of said cylinder bore adjacent to said air inlet, said air inlet and air outlets being spaced from each other along the length of said handle portion, and a further air outlet from the end of said cylinder bore away from said air inlet, a differential piston in said cylinder bore having a larger diameter and a smaller diameter part, said piston having an axial bore therein opening out of the end of said piston at the larger diameter part, said smaller diameter part having a circumferential groove therein and four outlets opening into said groove from said axial piston bore and spaced at equal angles around said piston, and a closure cap closing the end of said piston bore, the length of the said driver from said collar to the end thereof adjacent said piston, plus the thickness of said collar and said spring when it is compressed is greater than the length of said body from the inner end of said driver bushing cap to said further air outlet, whereby said further air outlet always vents the inner end of said cylinder bore.

2. A motor for a pneumatic peening and marking tool, comprising a tool body having an enlarged handle portion on one end thereof, said body having a bore in the other end thereof with an enlarged outer end, a driver bushing cap in the outer portion of said enlarged outer end, a spring in said enlargement, the enlarged handle portion of said body having a cylinder bore therein joining the bore in said body, said handle portion having therein at least one threaded air inlet to said cylinder bore and two diametrically opposed air outlets from the portion of said cylinder bore adjacent to said air inlet, said air inlet and air outlets being spaced from each other along the length of said handle portion, and a further air outlet from the end of said cylinder bore away from said air inlet, a differential piston in said cylinder bore having a larger diameter and a smaller diameter part, said piston having an axial bore therein opening out of the end of said piston at the larger diameter part, said smaller diameter part having a circumferential groove therein and four outlets opening into said groove from said axial piston bore and spaced at equal angles around said piston, and a closure cap closing the end of said piston bore, whereby when a driver having a tool holding recess therein and having a collar thereon is placed in said tool body, it will project from said body and said spring will fit between said collar and the bushing cap and urge said driver away from the end of said body in which said driver bushing is pushed.
